BOY D. MAILEY, OF EAST ORANGE, NEW JERSEY, ASSIGNOR TO COOPER HEWITT ELECTRIC COMPANY, OF HOBOKEN, NEW JERSEY, A CORPORATION OF NEW JERSEY.

CIRCUIT CONNECTER.

Application filed February 1, 1924. Serial No. 689,984.

- My present invention relates to electric switches of the liquid flow type and particularly to those in which the circuit is made and broken between two bodies of the conducting liquid of the switch, although my invention is also applicable to circuit makers and breakers where the current is broken between a solid conductor and the liquid of the switch.
- 10 In my device I use a cup of vitreous material which is capable of withstanding the high temperatures of an electric arc. This cup is positioned, in the closed circuit position of the device, substantially vertically and below the surface of the conducting liquid of the device and into the cup extends a solid electrode the outer end of which in the open circuit position of the device is above the level of the conducting liquid. The 20 cup completely encircles the part of the electrode passing into it so that when the main body of conducting liquid is caused to fall below the rim of said cup, as by tilting the device or otherwise lowering the level of said liquid in relation to said rim, the circuit is broken between the main body of liquid and that part of it which is still in the cup at the time the level of the main body falls below the rim of the cup. Should it be desired to have the circuit made and broken between the main body of the liquid and the conductor which terminates within said cup the relative positions of the said liquid and said conductor can accordingly be arranged, 30 but in either case the arc is broken over the rim of said cup. So, by making the cup of a very highly refractory material such as fused quartz glass or any other material having physical characteristics that will enable it to withstand the action of an electric arc I am enabled to use for the main body or envelope of a switch of this type much cheaper material and material which is less expensively worked. Within said body is 40 inserted during the process of its manufacture a cup such as I have described positioned about the end of one of the electrodes of the device and suitably secured therein as by means of one of said electrodes.
- 50 I shall describe my invention as being embodied in a mercury switch the envelope of which is of ordinary glass such as is used

for electrical purposes and in which the cup surrounding the end of one of the electrodes is of fused quartz glass.

It is the object of my invention to provide a switch of the liquid flow type in which the walls of the envelope of the device are not subjected to the corrosive and deteriorating action of the electric arc which is formed during the making and breaking of a circuit through the device.

It is a further object of my invention to provide a switch in which neither the envelope nor the solid electrodes of the device are subjected to the corrosive action of the electric arc.

It is also an object of my invention to make and break the circuit in a switch between two bodies of conducting liquid therein using a vitreous material of much higher melting point than that of the material of the switch envelope and capable of withstanding the temperatures incident to an electric arc.

In the drawings which form a part of this application Fig. 1, is a longitudinal mid-section view in elevation of a mercury switch having a tubular envelope through each end of which is sealed a solid conductor, one of which terminates below the surface of the mercury of the switch and the other of which terminates below said surface and within a cup of fused quartz which is positioned vertically in said switch and held in such position by the electrode which terminates within it and which is of such height as to separate the mercury into two bodies when the switch is tilted in the plane of the figure and away from said cup.

Fig. 2, is a view similar to that of Fig. 1 showing the switch in the tilted position and with the mercury separated into two bodies.

Fig. 3, is a vertical transverse section in elevation taken along the line 3—3 in Fig. 1 and looking in the direction of the arrows.

In the embodiment of my device as shown in the drawings the tubular envelope 1 has near one of its ends a substantially cylindrical flat bottomed depression. On this bottom is positioned vertically a cup 9 of fused silica which is held in such position by the electrode 3 which is sealed through

one end of the envelope 1 and which is through the hollow portion thereof, said bent downwardly into said cup and terminates therein with a loop or hook 8 fitting closely to the interior of the cup to hold 5 the cup in the desired position in relation to the other parts of the device and which is substantially vertical in the closed position of the switch. Through the opposite ends of the envelope 1 is sealed the electrode 5 10 which extends longitudinally and downwardly and terminates below the surface of mercury 6 of the switch which mercury is supplied to a level appreciably above that of the top of cup 9 in the closed position 15 of the switch.

In the open position of the switch such as is shown in Fig. 2, the mercury has been divided into two bodies by the rim of cup 9 over which any arc formed in the breaking of the circuit is formed without subjection of the material of the envelope wall to such an arcing.

It is understood that I am not limited in my invention to the relative positions of the cup, electrodes, and other parts of the device to that shown in the drawing. I intend my invention to cover any relative positioning suitable to the separating of the two bodies of mercury over the rim of a 30 cup of very highly refractory material without subjecting any other part of the switch other than the rim and sides of the said cup to the action of the arc formed in the making and breaking of the circuit through 35 the switch. Such a positioning would be for example: an electrode entering the cup of the switch through a point in the switch envelope directly above the center of the cup and terminating therein in such a manner as to position the cup properly as by being formed into a flat disk or spiral which rests against the bottom of the cup, or by being fused to the material of the cup on the inside thereof. Further I am 40 not limited to a switch in which the arc cup is positioned in a well or depression in the wall of the body of the switch. Such cup in some forms is positioned either on the 45 wall of the envelope or is suspended from the wall as by mounting it to the electrode which terminates within it, or supported by the other electrode to which it is mounted as by embedding such electrode in the outside wall of the cup.

50 Also when necessary, I supply the interior of my switch with a filling of a gas such as hydrogen, nitrogen, etc., for the proper extinguishing of the arc and for the conduction of heat therefrom.

55 Furthermore, in an embodiment of said switch, when desired I fire polish the rim of the member 9 to improve its arc resisting qualities. And in other embodiments where desired, I make the wall of the cup 9 hollow and circulate a cooling medium

7c

through the hollow portion thereof, said cooling medium serving to carry away the heat of the arc that is dissipated in contact with it. As will be readily understood this embodiment is particularly useful in breaking currents of large magnitude as compared with those now in common use.

Furthermore for some uses I make the cup 9 of ordinary vitreous material and provide it with a rim of arc resisting material that in the circuit breaking process the remainder of the cup is protected from the destructive action of the arc.

Furthermore I provide said cup 9 with an annular rim enveloping member sitting 80 on the rim of the cup 9 and held in place thereon as by the electrode 3 which terminates within the cup and the flanges of the annular member extending on the inside 85 and outside wall of the cup 9.

I claim:

1. In an electric device comprising a container, electrodes therein and liquid conducting material therein adapted to open and close a circuit to the container and means in said device for insuring making and breaking a current flow therethrough between liquid surfaces comprising a cup positioned about the end of one of said electrodes, said cup being of a more highly refractory material than that of said container, and being held in place in the container by the electrode terminating therein and the envelope wall.

2. In an electric device comprising a container, electrodes therein and a liquid conducting material therein adapted to open and close a circuit between said electrodes through the container and means for insuring the making and breaking of contact in said container at a point remote from the walls of said container, said means being held in position in the container by one of said electrodes and the container wall.

3. An electric switch of the liquid flow type comprising a sealed envelope, mercury in said envelope, electrodes sealed through the wall of said envelope and extending below the surfaces of said mercury in a closed position of the switch and a cup of refractory material about the end of one of said electrodes, said cup being held in place by the said electrode and the envelope wall.

4. An electric switch of the liquid flow type comprising a sealed envelope, mercury in said envelope, electrodes sealed through the wall of said envelope and extending below the surface of said mercury in a closed position of the switch and a cup of fused silica about the end of one of said electrodes, said cup being held in place by the said electrode and the envelope wall.

5. In an electric device comprising a container, a sealed envelope, mercury in said

100

envelope, electrodes sealed through the wall of said envelope and extending below the surface of said mercury in a closed position of the switch, a cup of refractory material 5 positioned about the end of one of said electrodes and held in place by said electrode and the envelope wall.

6. An electric switch of the liquid flow type comprising a sealed envelope, mercury 10 in said envelope, electrodes sealed through the wall of said envelope and extending below the surface of said mercury in the closed position of the switch, and a cup of refractory material about the end of one 15 of said electrodes, said electrodes serving to

hold said cup in position against the envelope wall.

7. An electric switch of the liquid flow type comprising a sealed envelope, mercury in said envelope, electrodes sealed through 20 the wall of said envelope and extending below the surface of said mercury in a closed position of the switch, and a cup of refractory material about the end of one of said electrodes, said electrode being formed to 25 hold the cup in position.

Signed at Hoboken in the county of Hudson and State of New Jersey this 31 of January, A. D. 1924.

ROY D. MAILEY.
